DISPLAY DEVICE

Joseph Schick, Brooklyn, N. Y., assignor to Baker
Brush Co. Inc., New York, N. Y.

Application August 19, 1937, Serial No. 159,831

1 Claim. (Cl. 211—49)

This invention relates to new and useful improvements in display devices and more particularly it pertains to devices for displaying various articles of which paint brushes are one good 5 example.

It is the object of the invention to provide new and novel means for displaying paint brushes and similar articles, and at the same time keep them orderly and in pre-determined 10 numbers in groups.

It is a further object of the invention so to construct the device that it may be used in various different manners.

Still a further object of the invention resides in 15 a novel construction and arrangement of parts whereby each time a paint brush is removed from the device, a signal will be given.

Still a further object of the invention resides in a new and novel construction which is simple 20 in operation and economic of manufacture.

With the above and other objects in view reference will be had to the accompanying drawings, in which:

Figure 1 is a perspective view of one of the units 25 forming an important part of the device,

Figure 2 is a longitudinal sectional view on an enlarged scale taken substantially on the line 2—2 of Figure 1,

Figure 3 is a transverse sectional view taken 30 substantially on the line 3—3 of Figure 2,

Figure 4 is a perspective view of a removable panel member,

Figure 5 is a longitudinal sectional view taken 35 substantially on the line 5—5 of Figure 4,

Figure 6 is a perspective view illustrating the manner in which the panel member as illustrated in Figures 4 and 5 is employed in combination with a unit,

Figure 7 is a sectional view taken substantially 40 on the line 7—7 of Figure 6, the view being on an enlarged scale, and;

Figure 8 is a perspective view illustrating the manner in which a number of units may be secured together to provide a multiple unit display 45 device.

Referring to the drawings, and particularly to Figures 1 to 3, the device comprises a base member A. This base member A is formed from semi-flexible material such for example as sheet 50 metal and has an inclined top wall 10. This inclined top wall 10 has a plurality of openings 11 arranged in pairs, which openings preferably extend in a straight line transversely of the top wall 10. The base member, as illustrated in 55 Figure 2, has a bottom wall 12 which is bent up-

wardly at its free end as at 13, and suitable supporting feet 14 are provided.

Extending transversely of the under face of the inclined top wall 10 there is a rigid member 15, and this rigid member is secured as by nails, 5 screws or the like 16 to the inner face of the inclined top wall 10. This rigid member provides the means for carrying a plurality of article retaining elements 17. As best illustrated in Figure 1, these elements 17 are arranged in pairs 10 and, as shown in Figure 3 the elements in each pair are angularly disposed in such manner that they converge towards each other. An enlarged head portion 18 is formed upon the free end of each of these elements 17 preferably by forming 15 a turn in the end of the member, it being understood that the member is formed from wire or similar material.

By this construction and arrangement of parts, the article, which in the present instance is a 20 paint brush, may be positioned upon the inclined wall 10 with its handle between the elements forming one of the pairs of elements, and said brush will be retained in position by the means 17. By angular disposition of the elements 17 25 in each pair, the space between the enlarged head portions thereof is contracted so that the elements will be set in vibration by the removal of a brush from its display position, and this vibration will set up a sound of a more or less 30 musical character and attract attention to the fact that a paint brush is being taken from the display. This is an important feature of the invention since it lessens the possibility of picking up of the paint brushes or other articles with- 35 out being observed by the clerk or attendant.

Extending upwardly from the rear end of the base member A there is a member B. This member B is formed of sheet metal or other similar semi-flexible material and has an inclined front 40 wall 20 from which project rearwardly extending sides 21. Flanges are provided and screws or the like 22 are employed to secure this member B in position upon the base member 10.

It will be obvious that the top wall 10 of the 45 base member A and the front wall 20 of the base member B may be provided with any advertising copy desired.

In Figures 4 and 5 I have shown a panel which comprises a main body portion 30 formed of sheet 50 metal or similar material. This body portion 30 has side flanges 31 which are provided with elongated openings 32. The panel 30 may be supported in display position in which it is illustrated in Figure 5 by an easel or the like 33, the 55

end portions 34 of which are off-set and receive the eyes 35 secured to the rear face of the panel 30. This panel member 30 is provided with the article holding means heretofore described and 5 serves to support the articles to be displayed upon the front face thereof when the device is in display position.

The panel member 30, as shown in Figure 6, may be used in combination with one of the units 10 comprising the members A and B, and when this is done, the panel member is placed with its flange adjacent one side wall of the member 20 and a bolt 35 is passed through the opening 32 in the flange 31 of the member 30, and an opening 36 15 in one of the side walls 21 of the member B. By this construction it will be obvious that the panel member 30 may be secured in position to support a plurality of articles which will be elevated with respect to those carried by the base member A.

It will be obvious by reference to Figure 8 20 that several of these units may be secured together to form a single display device and when this is done the panel member 30, heretofore referred to, is secured to the member B of the central unit A and to the member B of each of the 25 end units by bolts such as 35, heretofore described.

From the foregoing it will be apparent that the present invention provides a new and improved display device which is particularly adapted for the display of paint brushes and similar articles, and while the invention has been herein disclosed in the preferred form, it is to be understood that it is not to be limited to the specific construction herein illustrated and that it may be practiced in other forms without departing 5 from the spirit thereof.

Having thus described the invention, what is 10 claimed as new, is:

A display device comprising a plate or panel-like member of semi-flexible material having a transversely extending series of openings intermediate the ends thereof, a stiffening element secured to said panel-like member and extending transversely of the rear face thereof and positioned directly in line with said openings, a plurality of U-shaped resilient members projecting 15 through said rigid members and the openings in the panel-like member with the legs of each U-shaped member in converging relation, and means for securing the rigid member permanently to the rear face of the panel-like member. 20

JOSEPH SCHICK.
